M. B. KING,

YARN GUIDE.

APPLICATION FILED MAR. 28, 1919.

1,316,452.

Patented Sept. 16, 1919.

2 SHEETS—SHEET 1.

Fig. 1.

A

A technical line drawing of a mechanical assembly, labeled "Fig. 2." at the top. The drawing shows a horizontal beam supported by a central pivot. On the left side, a vertical plate labeled 8 is attached to the beam. A curved bracket labeled 11 is also attached to the beam. On the right side, a vertical plate labeled 7 is attached to the beam. Two vertical cylindrical components, labeled 10, are mounted on the beam. Each cylinder has a small rectangular block labeled 14 at its top. Between these two cylinders is a vertical tube labeled 13, which has a small rectangular block labeled 17 at its top. A small circular component labeled 12 is positioned between the two cylinders. A horizontal tube labeled 6 is attached to the beam, and a small circular component labeled 7 is attached to the end of this tube. A curved bracket labeled 2 is attached to the beam below the main assembly. A small rectangular block labeled 3 is attached to the beam near the bottom. The entire assembly is mounted on a base labeled 1.

UNITED STATES PATENT OFFICE.

MANUEL B. KING, OF NEW BEDFORD, MASSACHUSETTS.

YARN-GUIDE.

1,316,452.

Specification of Letters Patent. Patented Sept. 16, 1919.

Application filed March 28, 1919. Serial No. 285,904.

To all whom it may concern:

Be it known that I, MANUEL B. KING, a citizen of the United States, residing at New Bedford, in the county of Bristol and 5 State of Massachusetts, have invented new and useful Improvements in Yarn-Guides, of which the following is a specification.

This invention relates to improvements in yarn guides and tension devices and the 10 principal object of the invention is to provide means for making the guide adjustable to suit different sizes of yarns and to combine with the guide interchangeable tension rollers so that a roller of the proper size 15 may be used.

Another object of the invention is to provide means for holding the bobbin in position.

The invention also consists in certain other 20 features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:

30 Figure 1 is a view showing the invention in use;

Fig. 2 is an enlarged side view of the guide and tension device;

Fig. 3 is a plan view of this device;

35 Fig. 4 is a rear view thereof;

Fig. 5 is a sectional detail of the roller.

In these views 1 indicates the base of the guide which is provided with the downwardly projecting lugs 2, one of which carries the screw 3 for securing the device to a part of the frame. At one end the base is provided with the V-shaped opening 4 ending in the slot 5 for receiving the yarn. The upper face of the base is provided with 40 the three upwardly extending ears 6 through which the pivot pin 7 passes. Between the outermost lugs the arm 7 of the yarn guide passes and is pivoted on the pin. A plate 8 is secured to the end of this arm and extends at right angles thereto. The arm is provided with a pair of screw-threaded holes 9 which receive the adjusting screws 10 which are located one on each side of the

arm. It will thus be seen that the arm may be adjusted by these screws so as to occupy 55 any desired position in relation to the base. A pin 11 is supported at the edge of the base adjacent the lower edge of the plate 8 and this pin acts as a stop for the yarn. The short arm 12 is also pivoted to the pin 7 60 and is located between the two inner ears 6 as shown. The outer end of this arm carries a roller 13. This roller is detachably secured to the arm by means of a bolt 14 passing through a bore 15 in the roller and 65 having its screw-threaded end 16 engaging a hole in said arm and receiving a nut 17 which holds the bolt on the arm. This bolt is provided with a screw head 18. I provide a plurality of these rollers of different sizes 70 so that one roller can be replaced by a roller of a different size when it is desired to use devices for yarn of a different size. It will thus be seen that the guide plate 8 may be adjusted to suit different sizes of yarns and 75 by placing the proper sized roller on the arm the proper tension is placed on the arm.

As shown in Fig. 1, the yarn passes from the bobbin A through my improved device shown at B to the spool C. 80

It is thought from the foregoing description that the advantages and novel features of my invention will be readily apparent.

I desire it to be understood that I may make changes in the construction and in the 85 combination and arrangement of the several parts, provided that such changes fall within the scope of the appended claims.

What I claim is:

1. A device of the class described, comprising a base, ears projecting upwardly therefrom, a guide having an arm pivoted between said ears, an arm also pivoted to said ears and a roller detachably connected to said arm. 90

2. A device of the class described, comprising a base having a yarn-receiving opening therein, clamping means on the underside of the base, ears projecting upwardly from the base, a stop pin on the base, a guide having an arm pivoted to said ears, screw bolts on said arm for adjusting the same, a second arm, and a roller detachably connected to said second arm. 100

In testimony whereof I affix my signature. 105
MANUEL B. KING.
